ROCKING CHAIR

Richard Morse Chapin and Hamlin Taylor Haynes, Charlotte, N.C., assignors to Paoli Chair Company, Inc., Paoli, Ind.

Filed Aug. 5, 1974, Ser. No. 495,049

Term of patent 14 years

Int. Cl. D6—01

U.S. Cl. D6—49

Fig. 1

Fig. 2

Fig. 4

Fig. 3

FIG. 1 is a side elevational view of a rocking chair, FIG. 2 is a front elevational view thereof, FIG. 3 is a back elevational view thereof; and FIG. 4 is a perspective view thereof, this view omitting the cushion shown in FIG. 1 for the purpose of clarity in showing the complete design.

We claim:

The ornamental design for a rocking chair, as shown and described.
